AIR COMPRESSING APPARATUS

Lindsay H. Browne, Pittsford, N. Y., assignor to
 Kellogg Compressor and Manufacturing Cor-
 poration, a corporation of New York

Application July 28, 1937, Serial No. 156,075

7 Claims. (Cl. 230—58)

This invention relates to improvements in air compressing apparatus.

An object of the invention is to provide an improved air compression unit including compressor, motor, storage tank and accessories.

Another object is to provide a unit of the above nature which is quiet and smooth and efficient in operation.

A further object is to provide a unit of the above type in which the motor and compressor are supported on the tank by vibration absorbing means eliminating all metallic connections between the elements.

Still another purpose is to provide improved discharge means for delivering the compressed air into the storage tank by which noise due to drumming or pulsation of the discharge is eliminated, and by which any leakage from the valve outside the tank is rendered impossible.

Another purpose is the provision of a unit including a compound compressor having improved head and valve structure, and in which the crankcase is sealed from the outer air.

A still further object is to provide improved means to cool the air between stages and before delivery to the storage tank.

Other objects and advantages of the invention will become evident during the course of the following description in connection with the accompanying drawings, in which—

Figure 1 is a perspective view of a preferred form of the invention;

Figure 2 is an exterior detail view of the resilient discharge connecting device;

Figure 3 is a plan view of a preferred form of resilient mounting device;

Figure 4 is a vertical sectional view of the same;

Figure 5 is a longitudinal sectional view of one form of the discharge check valve;

Figure 6 is an end elevation of the same;

Figure 7 is a side elevation of the same;

Figure 8 is a longitudinal sectional view of an alternative form of discharge check valve;

Figure 9 is an end elevation of the same;

Figure 10 is a detail view of the discharge check valve disc shown in Figure 8;

Figure 11 is a detail view of the spring retainer for the same;

Figure 12 is a horizontal sectional view of the cylinder head;

Figure 13 is a bottom view of the same;

Figure 14 is a detail view of the valve seat ring;

Figure 15 is a similar view of the valve retainer ring;

Figure 16 is a detail view of the valve plate; and

Figure 17 is a vertical fragmental sectional view of the first stage suction and discharge valve structures and mounting taken on the line 17—17, 5 Figure 12.

Referring to Figure 1, the numeral 20 indicates a storage tank provided with feet 21 and pressure gage 22. Brackets 23 welded to the tank 20 have secured thereto resilient mounting pads 24, preferably of the structure shown in detail 10 in Figures 3 and 4.

Referring to the latter figures, the pad 24 consists of a cupped metallic mounting plate 25, a rubber body 26 secured into and extending 15 above the plate 25, and a central bolting cup 27 of metal secured in the body 26 and resiliently separated thereby from the mounting plate. The plate 25 and cup 27 are preferably made of stampings provided with tongues 28 and 29 embedded in the rubber body 26, the entire assembly 20 being permanently vulcanized together. The mounting plate 25 has lugs 30 provided with holes 31 through which the pad is bolted to the brackets 23, Figure 1, and central holes 32 in 25 the bolting cups 27 accommodate bolts 33, Figure 1, by means of which a frame or base 34 is secured to the pads.

From the foregoing it will be seen that the base 34 and tank 20, while firmly connected, are 30 resiliently insulated from each other by the pads 24.

Secured on the base 34 is a compressor 35, preferably of the two-stage type, and a suitable driving motor 36. The compressor 35 has a triple 35 grooved flywheel 37 acting as a pulley and driven through three V-belts 38 from the motor pulley 39. The spokes 40 of the flywheel 37 are formed as fan-vanes, which when in motion provide a blast of cooling air as hereinafter set forth.

The compressor 35 is equipped with a head 41 of a type shown in detail in Figures 12, 13 and 17, the head being bolted to the cylinder block 42, Figure 1. The block 42 has a low pressure or first stage cylinder 43 and a high pressure cylinder 44, the lines on which the inner circumferences of these cylinders register with the head 41 being indicated by dotted and dashed lines 45 and 46 respectively on the bottom view of the head, Figure 13.

A suction or inlet elbow 47, Figures 12 and 13, preferably integral with the head 41, leads into an inlet pocket 48. Two valves 49 and 50, constructed in a manner hereinafter described, permit the passage of air from the pocket 48 to the 55

first stage cylinder 41. A second pair of valves 51 and 52 permit discharge of air from the cylinder 41 to a second pocket 53, from which a connector elbow 54, Figures 1 and 12, conducts the air to a finned tube 55. The tube 55 is formed in a loop disposed in position to receive a blast of cooling air from the fan-blade spokes 40 of the flywheel 37, and leads through a second elbow fitting 56, Figure 12, into the inlet pocket 57 of the second or high pressure stage of the compressor. The finned tube 55, so disposed as to receive the cooling blast from the flywheel, this operates as an inter-cooler between stages of the compressor to dissipate heat of compression from the first stage.

From the pocket 57 a valve 58, of construction identical with that of valves 49 and 50, admits the air to the high pressure cylinder 44 from which after compression it is discharged through a valve 59 and pocket 60 to a discharge tube 61 hereinafter described.

All the valves noted above are of identical construction, consisting of parts shown in detail in Figures 14, 15, 16 and 17. These parts consist of a seat-ring 62, a guide cup 63, a valve plate 64 and a conical compression spring 65.

The seat-ring 62 has a flat annular seat portion 66 raised slightly above the outer rim of the ring and above a central depression 67, the seat portion 66 being pierced by a plurality of arcuate slots 68.

The guide cup 63 consists of a short cylindrical barrel 69 formed integrally with a flat perforated head or spider 70. Both the seat ring 62 and guide cup 63 are threaded on their peripheries.

The valve plate 64 is of thin resilient steel, and is hexagonal in shape in rounded corners 71 and a central hole 72.

Figure 17 shows in sectional detail the manner in which two identical sets of the above parts are disposed in the head 41 to form inlet valve assembly 49 and discharge valve assembly 51.

Referring first to the inlet valve assembly 51, Figure 17, it will be seen that the seat ring is screwed against a shoulder 73 at the upper end of a threaded hole 74 leading from the lower face of the head 41 to the pocket 48, the annular seat portion 66 being directed downwardly. The thin valve plate 64 is held against the seat 66 by the conical spring 65, covering the arcuate slots 68. The guide cup 63 is screwed into the threaded hole 74, the end of the cylindrical barrel 69 tightly engaging the rim of the seat-ring 62 and locking both parts in place. The rounded corners of the valve plate 64 fit loosely inside the barrel 69 which thus serves to guide the valve plate, the spider 70 serving to hold the spring 65 in compression against the valve plate to urge the latter against its seat 66.

The end of the barrel 69 is bevelled at 75 and the shoulder 73 may be grooved or undercut at 76, thereby providing narrow circles of contact between the mating parts and permitting air-tight joints without the use of gaskets.

When by descent of the piston in the compressor cylinder 43 a partial vacuum is created therein below the head 41, the preponderance of pressure in the inlet pocket 48 acts through the arcuate slots 68 to press the valve plate 64 downward from its seat 66 allowing air to pass through the spider 70 and into the cylinder. In its passage the air passes around the hexagonal periphery of the valve plate and also through the central hole 72, giving a relatively large area of inlet opening with very small motion of the valve plate. This fact,

together with the extreme lightness and resilience of the valve plate, results in very quiet valve action and low resistance to the passage of air, which advantages are further augmented by the use of the two identical inlet valve assemblies 49 and 50 to divide the total volume drawn into the compressor.

The discharge valve assembly 51 is identical with the inlet valve assembly 49 described above except that the entire assembly is inverted, the head or spider end of the cup 63 being screwed against the shoulder 73 and the seat ring 62 becoming the locking member. The operation of the valve is the same as described except, of course, that it permits discharge of air from the first stage cylinder 43 to the inlet pocket 57 of the high pressure cylinder.

The inlet and outlet valves 58 and 59 of the second or high pressure stage are identical in structure with those described. Thus all valves are interchangeable, a condition highly advantageous both from the view-points of manufacture and service. The simple and compact standardized valve structure allows great flexibility in design of the compressor for different sizes and capacities, as the valves may be disposed singly or in multiple in any desired combination. To widen the field of capacities for which the compressors are designed, a second standardized valve assembly may be provided, identical in structure with that described above, but of smaller size, and in some cases assemblies of both sizes may be embodied in one compressor in order to achieve the most advantageous spacing, grouping and capacity of valves.

The discharge tube 61, previously referred to, is composed of externally finned tubing. It is formed in a loop encircling the shaft of the compressor in the zone of air blast from the flywheel fan spokes 40 as shown in Figure 1. The tube 61 thus constitutes an after-cooler giving up heat of compression to the flywheel air-blast in the same manner that the loop 55 operates as an inter-cooler.

The discharge tube 61 terminates in a union 77 to which is secured a length of resilient hose or tube 78, Figures 1 and 2, preferably of a reinforced synthetic rubber construction. The other end of the resilient section 78 is secured to a threaded connector 79 which is screwed tightly into the inlet end 80 of a check valve assembly 81 shown in detail in Figures 8, 9, 10 and 11.

Referring to Figure 8, it will be seen that the check valve unit 81 has a body 82 into which is threaded a cap 83 formed with a constricted central nozzle 84 and enclosing a cylindrical chamber 85. A resilient seat ring 86, of rubber or the like, is fitted into an annular recess in the body 82, a thin cylindrical inner wall 87 of the latter extending substantially through the rubber ring so that the latter is rigidly supported against distortion, on its inside as well as on its outside circumference. A valve disc 88 has a raised annular portion 89 engaging the seat ring midway between the latter's inner and outer circumferences. Small radial projections 90 on the valve disc serve to guide the disc loosely in the bore of the chamber 85 and thereby ensure proper concentric engagement of the disc and seat.

The valve disc 88 is urged against the seat ring 86 by a compression spring 91 guided on a tapered spud 92 secured in a cross member 93 which spans the chamber 85 and presses against a shoulder 94, Figure 8. A short cushioning spring 95, secured in a recess 96 in the spud 92, serves as a resilient

stop to limit the opening motion of the valve disc 88.

The body 82 is provided with an exterior tapered thread 95 which is screwed into a suitable fitting 96 in the top of the tank 20, Figure 1. Thus, the entire valve mechanism projects inside the tank 20, and there are no exterior joints in the check valve assembly through which leakage might occur to the outer air.

In operation, the chamber 85 and restricted nozzle 84, both located inside the tank 20, act as a muffler for discharge of compressed air into the tank. Any pulsations of air through the valve are equalized in the chamber 50 so that the discharge of the air through the nozzle 84 occurs smoothly and at a practically constant rate. By this means "drumming" or audible vibration of the air discharge into the tank is eliminated. The motion of the valve disc 88 takes place entirely between resilient limiting means, that is, between the rubber seat ring 86 and the stop spring 95, so that no clicking or hammering can arise at this point. The combination of this valve action and the elimination of pressure pulsations as described above results in a substantially silent air discharge into the tank 20.

The contact of the valve disc with the middle portion of the face of the rubber seat 86, and the latter's rigid support, as previously set forth, resulting in long seat life and sustained tightness of the valve.

A tapped hole 97 in the valve body 82 near its inlet end 80 is provided to permit connection by means of a small flexible tube 98, Figure 1, to a combined pressure switch and magnetic unloader 99 mounted on the base 34 behind the motor 36. The structures of such pressure switches and unloaders are well known to those skilled in the art and therefore are not described herein, their functions being to break the motor circuit when the pressure in the discharge line rises to a predetermined point and at the same time to exhaust the discharge line to the atmosphere through the tube 98, so that restarting of the compressor occurs only against atmospheric pressure.

With small compressors an alternative form of check valve unit shown in Figures 5 and 6 may be used, in which the body 100 is constructed at 101 for a tubing union connection. The cap 102 encloses the equalizing chamber 103 in which is guided a light disc valve 104 and its compression spring 105. The cap 102 has an exterior annular stepped groove 106 from which a hole 107 leads into the chamber 105. A resilient metal clip 108 is sprung into the outer step of the groove 106, leaving a slotted opening 109 disposed circumferentially opposite to the hole 107.

In operation, the alternative valve unit functions in substantially the same manner as previously described. Some of the air from the equalizing chamber 103 escapes directly through a small hole 110, but the major portion is forced to pass out the hole 107, thence around the annular passage formed by the groove 106, and finally out at the slot 109. By the restriction and labyrinthine passage of the air from chamber 103, pulsations and drumming are eliminated as previously set forth.

The crank case 111 of the compressor 35, Figure 1, is not provided with the usual atmospheric breather, but instead a pipe 112 leads from the crank case to a tapped boss 113 in the inlet el-

bow 47. A combined inlet muffler and air filter 114, secured to the end of elbow 47, silences and filters all inlet air drawn into the compressor. The connection of the pipe 112 as described allows the crank case to be sealed from the outer air, all "breathing" taking place with filtered air from the muffled inlet passage. Contamination of the crank case lubricant with dust and dirt is thereby avoided, and the "panting" sound common to open breathers is entirely eliminated.

From the foregoing description it will be seen that the cooperation of the features of the invention set forth throughout cooperate to produce a silent and efficient compressing unit. Pneumatic noises are eliminated by the inlet muffler, internal breather, light and efficient compressor valves, and the combined check valve and discharge muffler structure, while the resilient connection of the compressing mechanism to the tank 20 by means of the pads 24 and the flexible discharge coupling 78 prevents transmission of any mechanical or electrical vibrations to the tank and its foundation.

The location of the finned inter-cooler 55 and after-cooler 61 in the air-blast of the flywheel 37 contribute to the quietness of the machine by eliminating auxiliary fans, and the shape and large cooling surface of these members exposed to the air blast, in cooperation with extensive cooling fins 115 on the cylinder head 41, provide thorough dissipation of the heat of compression prior to delivery of air to the storage tank 20.

While the invention has been described in preferred form, it is not limited to the precise structures set forth, as various modifications may be made without departing from the scope of the appended claims.

What is claimed is:

1. In an air compression device, in combination, a storage tank, a plurality of resilient pads secured to said tank, a compressor base mounted on said pads and secured thereto, a compressor on said base, a motor on said base and connected to said compressor to drive the same, a discharge line on said compressor, a discharge check valve within said tank, means including a resilient tubular coupling joining said discharge line to said check valve, and control means including means to release the pressure from said discharge line and resilient coupling.

2. The combination claimed in claim 1 wherein said control means includes means on said base and responsive to pneumatic pressure to control the operation of said motor and compressor, and a resilient tube adapted to transmit discharge pressure from the inlet side of said check valve to said control means.

3. In a device of the character described, in combination, a storage tank, a compressor resiliently mounted thereon, a discharge line on said compressor, a check valve in said storage tank, a resilient coupling connecting said discharge line to said check valve, and resiliently connected means to unload pressure from said line and coupling.

4. In a device of the character described, a compressor having a closed crank-case, an inlet pipe, means attached to said inlet pipe to silence the intake of air to said pipe and to filter said air, and a breather pipe leading from said crank-case into said inlet pipe between said means and said compressor.

5. In a device of the character described, an air compressor having a discharge line and

- means to unload pressure from the same, a storage tank, and a check valve unit connected to said line and secured to said tank in sealing relation, said unit comprising an elongated body 5 projecting into said tank, a check valve in said body within said tank, and means in said tank to retain said valve in said body.
6. In a device of the character described, a discharge check valve unit comprising a body having 10 an inlet passage therethrough, a closure cap on said body and forming therewith an enlarged expansion chamber at the inner end of said passage, said cap having a constricted outlet therethrough, a resilient seat ring in said body 15 rounding the entry of said passage to said chamber, a valve disk guided in said chamber, and a spring urging said disk against said seat ring, said cap having a circumferential groove with stepped sides and a hole connecting said groove with said 20 chamber, and including a snap ring disposed in the outer step of said circumferential groove, said

snap ring having a slot spaced circumferentially from said hole whereby an exit from said chamber is provided through said hole, around the inner step of said groove and through said slot.

7. In an air compression device, in combination, a storage tank, a plurality of resilient pads secured to said tank, a compressor base mounted on said resilient pads, a compressor on said base, said compressor having an inlet pipe and a closed crank-case, means on said inlet pipe to silence 10 the intake of air thereto, a breather tube connecting said crank-case to said inlet pipe between said silencing means and said compressor, a discharge line on said compressor, a check valve in said tank, means including a resilient 15 coupling connecting said discharge line to said check valve, means to silence the discharge of air through said valve into said tank, and unloading means to release the pressure from said discharge line.

LINDSAY H. BROWNE.
